CRANKCASE VENTILATION SYSTEM

John W. Humphreys, Muskegon, Mich., assignor to Johnson Products, Inc., Muskegon, Mich., a corporation of Michigan

Filed Jan. 22, 1964, Ser. No. 339,391

5 Claims. (Cl. 123—119)

This invention relates to a crankcase ventilation system, and more particularly to a unique crankcase air intake valve in combination with a positive pressure crankcase exhaust control system to the intake manifold.

This invention relates to my prior invention in Patent No. 3,108,581, assigned to the assignee herein.

My prior invention, disclosed and claimed in the above identified patent, utilizes a sealed crankcase exhausting system to the intake manifold. A flow control valve is in the connecting conduit. It allows flow of blow-by gases from the crankcase to the manifold when opened by a control element exposed on one side to atmospheric or other standard pressure and on the other side to positive crankcase pressure. Thus, it opens in response to the excess of crankcase pressure over atmospheric pressure to exhaust blow-by gases to the manifold. No gases are allowed to flow out of the sealed crankcase to the atmosphere. Also, the usual substantial air intake directly from the atmosphere to the crankcase is eliminated, to thereby control sludging due to cold air flow and dust into the crankcase.

Extensive testing and use of the patented system on vehicles of various types has proven its uniqueness, operativeness, and advantages. However, recent testing and use of the system on engines of road-type vehicles having engines at least partially worn, has shown the necessity of a modification of the system for optimum performance under these conditions.

It has been found that worn engines employing the novel system on a sealed crankcase experience a substantial crankcase vacuum or negative pressure when the vehicle is decelerating under closed throttle conditions. Closed throttle deceleration typically occurs when a vehicle is using the engine as a braking force, for example, when going down a long hill. The vacuum is caused by the continued reverse flow of gases from the crankcase through the engine cylinders around the pistons to the combustion chambers, instead of vice versa.

This phenomenon and its result can be explained as follows: An engine is normally operating as an air pump. Air is pumped through the carburetor and induction system by the downward motion of the piston. During this time, the intake valve is open. The intake valve is then closed and the air mixed with fuel from the carburetor is compressed by the upward motion of the piston. The charge is then fired by the spark plug, pushing the piston downward for the power stroke. The exhaust valve is opened after the power stroke and the piston returns to the upward position, pushing the burned exhaust gases into the exhaust manifold and out to the atmosphere. The amount of air being pumped through the engine depends on the position of the carburetor throttle plate. During deceleration, with the throttle plate closed, practically no air is pumped through the engine because of the restriction at the carburetor. The pumping effort, however, is being continued by the pistons. The result is that a high vacuum (up to 26" Hg) is created in the intake manifold. During the intake stroke of the piston, this vacuum is also present in the combustion chamber and the combustion cycle produces relatively little pressure rise in the combustion chamber. Since the average combustion chamber pressures during deceleration are well below atmospheric pressure, crankcase gases are drawn past the piston rings into the com-

2

bustion chamber, and past the intake valve-to-valve guide clearance into the intake manifold. As an engine wears, the amount of gases drawn from the crankcase during deceleration increases, which reduces crankcase pressures below atmospheric pressure to such an extent as to be detrimental.

It is an object of this invention to provide a pressure operated crankcase ventilation system as useful for worn engines of road vehicles as engines in good condition, by providing a crankcase ventilation cap that prevents any crankcase exhaust flow to the atmosphere, but also prevents any substantial vacuum or negative pressure from forming in the crankcase.

It is another object of this invention to provide an internal combustion with controlled gaseous flow and complete pressure control between the intake manifold, the crankcase, and the atmosphere, to effect optimum operating conditions with minimum sludge formation in the crankcase and no exhausting of noxious fumes from the crankcase to the atmosphere.

Still another object of this invention is to provide a crankcase ventilation system useful for any internal combustion engine without adjustments or modifications to suit the particular engine, and which remains highly effective to control gaseous flow in worn engines of road vehicles.

A further object of this invention is to provide a crankcase exhaust control system that prevents exhaust outflow to the atmosphere and admits small controlled amounts of air to the crankcase from the atmosphere just sufficient to prevent detrimental excess vacuum but small enough to limit sludging to an insignificant amount.

Another object of this invention is to provide a crankcase ventilation system especially useful for worn engines that are subjected to closed throttle deceleration.

Another object of this invention is to provide a novel crankcase filler tube cap with the capacity of controlling atmospheric air intake into a sealed crankcase in regulated small quantities to prevent substantial crankcase vacuum, by effecting one-way flow control to the crankcase, and preventing exhausting of noxious fumes to the atmosphere while allowing limited influx of atmospheric air with minimum sludging.

These and several other objects of this invention will become apparent upon studying the following specification in conjunction with the drawings in which:

FIG. 1 is an end elevational view of an engine of this inventive combination;

FIG. 2 is a side elevational view of the novel oil filler tube cap forming part of this system;

FIG. 3 is a sectional view of the cap in FIG. 2; and

FIG. 4 is a sectional elevational view of the pressure flow control part of the novel system.

The novel system 10 illustrated in FIG. 1 includes an internal combustion engine 12 having a crankcase 14, an intake manifold 16, and an oil pan 18, and a filler tube 20. The system includes gaseous vapor flow control means 22 from crankcase 14 to intake manifold 16, and includes crankcase vacuum relief means 24 in the form of an oil filler cap on filler tube 20.

The flow control cap 24 is formed of a housing shell 26, having a recessed area 28 to fit over the filler tube 20. The lower peripheral edge of the housing includes a planar, annular retention groove 30 receiving and retaining an annular resilient ring 32 preferably of a resilient rubber material to retain the cap on the filler tube by friction, and to seal the connection.

An annular dividing partition 34 extends across the central portion of the housing between its ends. It includes a central depression 36 forming a spring seat 37. The depression has an axial control opening 38 within the peripheral spring seat. The cross section of any

annular segment of this partition is an inverted U. (The downwardly depending peripheral flange 34 of the partition is deformed at right angles thereto and is secured to the peripheral inner wall of housing 26.) The pocket of the U receives an annular resilient stop 40 of rubber for abutment of the upper end of the filler tube 20. An upper annular valve seat 42 rests upon and is secured to the partition 34.

An annular filter 44 is positioned in the upper half of the cap between the upper end and the partition. It is between the central passageway portion of the cap and a plurality of atmospheric inlet ports 46. Consequently, a passageway means is formed from ports 46 through valve port 47, through depression port 38 and cavity 28 to the filler tube. This passageway and more specifically valve port 47, is normally closed by a plate type, one-way check valve 48 biased by an annular compression spring 50 against valve seat 42. The biasing force of this spring is calculated to cause the valve to open only with a predetermined pressure differential between atmospheric air at ports 46 and a negative crankcase pressure. Vapors from the crankcase cannot flow upwardly through the cap to the atmosphere.

The vapor flow of bypass gases from the crankcase 12 of engine block 12' (FIG. 4) to the intake system, and more specifically to the intake manifold 16, is achieved with flow control mechanism 22.

This flow control mechanism includes a conduit formed by connector 60, rubber hose 62 between this connector and the central conduit portion 64, rubber hose connector 66 between the central portion 64 and an outflow conduit 68 from the side pan 70 of the engine block. Preferably, an oil separator 72 is attached to the inside of the side pan to prevent oil flow up the conduit system.

A butterfly valve 76 is mounted on a pivot axis 78 in the central portion 64 to close off the passage when closed, and allow gaseous flow from the crankcase to the intake manifold when opened varying amounts. A pivot link 80 is affixed to shaft 78 externally of conduit section 64. The upper end of this link 80 is pivotally attached to a cross reciprocable link 82, the other end of which is affixed to retention plates 84 on opposite sides of diaphragm actuator 86. This diaphragm 86 is generally circular in configuration with link 82 attached to the center thereof. The periphery of the diaphragm is retained between two halves 90 and 92 of a pressure control housing. This pressure control housing has one side or chamber exposed to atmospheric pressure through ports 94, and the other side exposed to crankcase pressure through a crankcase pressure sensing tube 96. This tube extends from this chamber down to tube portion 64 on the crankcase side of butterfly valve 76.

In operation, check valve 48 in the filler cap is normally biased to a closed position. Under normal engine operating conditions, blow-by occurs from the cylinders of the engine past the pistons to increase crankcase pressure above atmospheric. The crankcase pressure in the conduit creates a positive pressure differential on diaphragm 86 over the atmospheric norm or standard, to shift the diaphragm. This shifts the linkage to rotate the butterfly valve a proportionate amount and allow crankcase gaseous flow past the valve into the intake manifold. As soon as the pressure differential disappears the valve is closed. The butterfly valve itself is not responsive to a pressure differential between the intake manifold and the crankcase. It is not opened by manifold vacuum. Rather the pressure responsive means or diaphragm 86 which controls the valve, opens it only in response to a positive pressure differential of crankcase pressure over the standard pressure, usually atmospheric. None of the crankcase vapors move into the chamber on the crankcase side of the diaphragm since this is a dead end passage. Consequently, contamination of the diaphragm is minimal. Also any de-

posits on the butterfly valve tend to be washed off by the self-washing nature of the apparatus.

After the engine becomes substantially worn, or partially so, if it is subjected to closed throttle deceleration, the gaseous movement due to the gases being pumped from the crankcase up around the pistons in the cylinders create a negative pressure in the crankcase. A substantial negative pressure in the crankcase can cause damage to the engine. Therefore, to relieve this condition, when the pressure differential between the atmospheric standard pressure and the negative crankcase pressure or vacuum becomes a predetermined amount, the pressure differential shifts the plate check valve 48 against the bias of spring 50. This allows entry of a small controlled amount of filtered atmospheric air into the crankcase to eliminate this differential. It will be realized that the amount of air necessary to relieve the vacuum is normally insignificant so that sludging caused by entry of cold air into the crankcase will not be a problem.

Therefore, no matter what the condition of the engine or the conditions of operation, the gaseous pressure conditions and flow are completely controlled throughout the crankcase and intake manifold system of the engine, to maintain at optimum performing conditions. Cold air entry into the crankcase is kept at a minimum. The crankcase is sealed to prevent exhausting of noxious fumes to the atmosphere.

Additional objects of this invention will occur to those skilled in the art upon studying the foregoing form of this invention and the principles involved. Also it is conceivable that certain structural modifications can be made in the system described or in the valving mechanism without departing from the inventive concept taught. Therefore, this invention is not to be limited to the particular details of the preferred form illustrated, but only by the scope of the appended claims and the reasonably equivalent structures to those defined therein.

I claim:

1. An engine assembly comprising: an internal combustion engine including a sealed crankcase and intake manifold means; conduit means extending from said sealed crankcase to said intake manifold means; gaseous flow regulator means for said conduit including a valving means and a pressure responsive element operatively associated with said valving means to open and close it; said pressure responsive element being responsive to the pressure differential between positive crankcase pressure over a standard pressure to open said valving means and allow flow of gases from said crankcase to said intake manifold upon an increase in crankcase pressure over said standard pressure and causing said valving means to close upon a decrease of crankcase pressure to said standard pressure; and a one-way normally closed valve between said crankcase and the surrounding atmosphere subject to opening upon a decrease in crankcase pressure a predetermined amount below atmospheric pressure to open and admit a small quantity of atmospheric air to said crankcase until crankcase pressure increases above said predetermined amount.

2. An engine assembly comprising: an internal combustion engine including a sealed crankcase and intake manifold means; conduit means extending from said sealed crankcase to said intake manifold means; gaseous flow regulator means for said conduit including a valving means and a pressure responsive element operatively associated with said valving means to open and close it; said pressure responsive element being responsive to the pressure differential between positive crankcase pressure over a standard pressure to open said valving means and allow flow of gases from said crankcase to said intake manifold upon an increase in crankcase pressure over said standard pressure, and responsive to close said valving means upon a decrease in crankcase pressure below said standard pressure; a one-way normally-closed flow control valving means between said crankcase and a gaseous supply means, preventing outflow of gases from said crankcase to the

atmosphere and responsive to open with a decrease of crankcase pressure below a predetermined minimum to allow gaseous inflow to increase said crankcase pressure above said minimum.

3. An engine assembly comprising: an internal combustion engine including an intake manifold and a sealed crankcase; a gas conduit between said manifold and crankcase; crankcase pressure responsive flow control valving means for said conduit for blow-by gases from said crankcase to said manifold; said flow control valving means being substantially responsive only to positive crankcase pressures over a standard pressure; and negative pressure relief means for said crankcase to relieve negative pressure occurring in said crankcase more than a predetermined value with respect to a standard pressure.

4. An engine assembly comprising: an internal combustion engine having an air intake means and a sealed crankcase; flow conduit means from said crankcase to said intake means; valve means in said flow conduit means, and valve actuator means responsive to a predetermined differential of crankcase pressure over atmospheric pressure to open and allow flow of blow-by gases from said crankcase to said intake means; and normally closed, one-way, vacuum-relief valving means between said crankcase and the atmosphere, responsive to a predetermined differential of atmospheric pressure over crankcase pressure to open and admit a controlled quantity of atmospheric air to relieve the vacuum.

5. An engine assembly, comprising: an internal combustion engine having an air intake means, a sealed crankcase, and a filler tube; flow conduit means from said crankcase to said intake means; valve means in said flow conduit means, and valve actuator means responsive to a predetermined pressure differential of crankcase pressure over atmospheric pressure to open and allow flow of blow-by gases from said crankcase to said intake means; oil filler cap on the end of said filler tube including seal means between said cap and filler tube; passage means through said cap communicant with said tube and the atmosphere; and normally closed valve means in said cap, openable against a bias only in response to a predetermined pressure differential of atmospheric pressure over crankcase pressure to allow inflow of regulated quantities of atmospheric air to relieve said pressure differential.
